(57) **CLAIM**

The ornamental design for a vehicle covering kit, as shown and described.

DESCRIPTION

FIG. 1 is a front view of a vehicle covering kit showing my new design;

FIG. 2 is a rear view of the vehicle covering kit;

FIG. 3 is a right side view of the vehicle covering kit;

FIG. 4 is a left side view of the vehicle covering kit;

FIG. 5 is a top view of the vehicle covering kit;

FIG. 6 is a bottom view of the vehicle covering kit;

FIG. 7 is a top front side perspective view of the vehicle covering kit; and,

FIG. 8 is a side view of the vehicle covering kit in use in an assembled position.

The broken lines in FIG. 8 are illustrative of environmental structure forming no part of the claimed design.
